UNITED STATES PATENT OFFICE.

JACOB HARRIS, OF MONTCLAIR, NEW JERSEY.

METATARSAL ADJUSTER.

1,091,931.

Specification of Letters Patent. Patented Mar. 31, 1914.

Application filed February 14, 1913. Serial No. 748,407.

To all whom it may concern:

Be it known that I, JACOB HARRIS, a citizen of the United States, residing in the town of Montclair, county of Essex, and 5 State of New Jersey, have invented new and useful Improvements in Metatarsal Adjusters, of which the following is a specification.

My invention consists of a device for the 10 support or adjustment of the metatarsal bones of the foot, whereby their derangement or dislocation may be corrected, and consists of the features of construction herein-after shown and described.

15 As the result of wearing ill-fitting shoes, and of other causes, the metatarsal bones are often deranged or their heads dislocated, thereby compressing the interosseous ligaments or nerves producing discomfort and 20 severe pain at the point of dislocation or derangement. the pain extending forward to the ends of the middle toes and often reverting into the arch of the foot. My improved device being placed under the heads 25 of the metatarsal bones, and extending under their articulations with the phalanges, lifts the joints back to their natural position, thereby removing the compression from the affected ligaments or nerves. The pad is 30 made of various sizes and thicknesses for accommodation to the size of the foot.

In the accompanying drawings forming part of this specification, Figure 1 is a side view of the left foot shown in a shoe, the 35 shoe being broken away to show the position of the adjuster and support; Figs. 2 and 3 are respectively perspective views of two forms of the adjuster and support, and Fig. 4 is a plan view of slightly different form.

40 The adjuster comprises an oval shaped pad 2, which is padded to give it proper thickness and shade, the rear end of which is secured to the band 3, which is intended to surround the shafts of the metatarsal 45 bones, as shown in Fig. 1, permitting unrestricted movement of the metatarsophalangeal joints, while the forwardly projecting pad supports these joints. The style of band 3 shown in Fig. 2, preferably of leather, 50 is laced at the top and intended for use with

a button shoe, the eyelet stays 4 meeting on the dorsal ridge; while with a laced shoe the form shown in Fig. 4 is used to avoid pressure upon the eyelet stays by the eyelets and lacing of the shoe. The band in Fig. 3 is 55 shown as a continuous elastic band which can be readily slipped over the foot and elastically grip the instep thus holding the adjuster in proper position.

The injury which my adjuster is designed 60 specifically to relieve is caused chiefly by wearing shoes which are too narrow, particularly shoes within which the sole is narrower than the foot so that the sides of the foot are raised above the middle portions of 65 the foot, thereby causing an injurious pressure to the nerve and ligaments along the upper surface of the middle of the foot. This pressure as stated above causes a severe pain which extends forward to the ends of 70 the middle toes and frequently up the middle of the foot into the arch. In my adjuster the pad is positioned so as to lie under the middle of the ball of the foot, but is not wide enough to extend to the edges of the sole, the 75 effect being to give the upper surface of the foot at the ball a lateral convex curve thereby relieving the pressure and counteracting the effect of the tight shoe. The pad is made of kid, or other soft leather, and stuffed with 80 hair or cotton, so as not to cause discomfort to the injured joints.

Having thus described my invention, what I claim and desire to secure by Letters Patent is:

85 In a device of the class described, a soft narrow pad of a width not greater than half the width of the foot, a band for holding said pad beneath the metatarsophalangeal joints of the middle toes, said band being attached to the rear end of said pad to lie to the rear of said joints so as not to interfere with the free movement of the foot.

90 In witness whereof, I have hereunto set my hand at Montclair aforesaid, this 12 day 95 of February, 1913.

JACOB HARRIS.
